FIG. 2

FIG. 3

FIG. 1 is a side elevational view showing my new design for a hat;

FIG. 2 is a top plan view thereof;

FIG. 3 is a front elevational view thereof; and

FIG. 4 is a rear elevational view thereof.

The characteristic feature of my design resides in the hat disclosed having particular downwardly curved lines of the brim at the front and back with the brim at each side having a slight upturn at its outer edge, all as shown in the drawing.

I claim:

The ornamental design for a hat, substantially as shown and described.
